Primary Examiner—Catherine E. Kemper
Attorney, Agent, or Firm—Delbert J. Barnard; Joan H. Pauly

[57] CLAIM

The ornamental design for a wood stove, substantially as shown and described.

DESCRIPTION

FIG. 1 is a front isometric view of a wood stove, showing my new design;

FIG. 2 is a top plan view thereof;

FIG. 3 is a front elevational view thereof;

FIG. 4 is a right side elevational view, the left side being a mirror image thereof;

FIG. 5 is a rear elevational view thereof;

FIG. 6 is a bottom plan view thereof.
